PERMANENT EXPANDER FOR SPLIT-SKIRT PISTONS

Frederick C. Dalton, Portland, Oreg., assignor of one-fourth to W. H. Darby, Salem, Oreg., and one-fourth to E. R. Dalton, Portland, Oreg.

Application March 24, 1938, Serial No. 197,911

10 Claims. (Cl. 309—12)

My invention relates particularly to the art of internal combustion engines and, more particularly, it deals with split skirt pistons.

Primarily, the invention has for an object to provide means to adjust the piston upon collapse, or upon wear of the piston-skirt and cylinder walls.

Further, it is an object to provide such adjusting means as can be operated without removing the piston, or taking down the engine after it has been once installed.

Again, the invention has for its object to provide a simple and effective way of effecting the adjustment by means of a tool inserted through a spark plug hole or other opening at the necessary place in the cylinder head of the engine.

Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawings, in which:

Fig. 1 is a section on the line 1—1 of Fig. 2, showing one embodiment of the invention.

Fig. 2 is a section on the line 2—2 of Fig. 1.

Fig. 3 is a cross section on the line 3—3 of Fig. 2.

Fig. 4 is a top plan view of the piston shown in Figs. 1 to 3.

Fig. 5 is a section on the line 5—5 of Fig. 6, showing another embodiment of the invention.

Fig. 6 is a section on the line 6—6 of Fig. 5.

Fig. 7 is a top plan view of the piston shown in Figs. 5 and 6.

Fig. 8 is an inverted plan view of the same.

Fig. 9 is an enlarged detail view of a portion of the adjusting screw showing its conical split end.

In the drawings in which like numbers indicate the same parts in all the figures, 1 is the head of the piston which has ring grooves 2; the skirt 3 is split at 4 and separated from the head at 18 and joined thereto at 19. The piston pin bosses are indicated by 5.

Projecting inwardly at each side of the split 4 is a lug 6. These lugs constitute a boss or guide for the tapered end 11 of the adjusting screw 10, the boss being tapered out, at 7, to fit the screw end.

The screw 10 is threaded into the boss 8 which, in the form of the invention shown in Figs. 1 to 4, inclusive, is made integral with the head and land

of the piston (see Fig. 2), the boss 8 being threaded at 9 for the purpose of receiving the screw.

The screw 10 has a suitable tool receiving kerf or recess 16 at its upper end, while at its lower end it has a tapered or conical portion 11 that is slit two ways at right angles, as at 12 (Figs. 2, 3 and 9), dividing such portion into four parts. By providing the split 12 the tapered end is rendered resilient so as to permit normal expansion and contraction of the skirt due to temperature changes without disturbing the setting of the screw and its adjustment effect on the skirt. This screw is made of special steel that will cause the four parts to possess spring-tension when the end 11 is screwed down in the boss 6—6.

The boss 8, it should be noted, does not join to the skirt 4 but is formed integrally with the piston head and land only.

The head 1 at the upper end of the threaded boss 8 is counterbored and threaded, as at 13, to receive the screw plug 14 that serves as a lock for the adjusting screw 10 and has a tool receiving recess 15.

Should the piston wear, as it does in the course of several thousand miles, all one would have to do is to take out screw 14 and turn down adjusting screw 10 to the right tension desired. This can be done with a tool inserted down through the spark plug hole, or some other opening at the necessary place in the head of the engine, thereby saving much time and expense.

The same scheme can be applied to ordinary split-skirt pistons now in use by providing them with separate screw-carrying bosses 8^a having a flange 20 for securing the same to the under side 35 of the piston head 1^a by means of screws 21, the boss being shaped to fit the piston, as shown, and having a portion 22 to underlie the land of the piston and project down into but out of contact with the skirt (see Fig. 6).

In Figs. 5 to 8, inclusive, those parts which correspond to like parts in the preceding figures bear the same reference number plus the index letter ^a, so a repetition of the description thereof is thought to be unnecessary. In the embodiment shown in Figs. 5 to 8, inclusive, no lugs (such as 6—6, in Fig. 2) are used, but the skirt at the slit 4^a is drilled or reamed, at 7^a, to fit the tapered end 11^a of the screw which projects into the slit.

Adjustment in the latter form of the invention 50 is made in the same manner as for the first form, once the piston is assembled in the engine.

Other modifications of the invention will be obvious to those skilled in the art.

From the foregoing description, taken in con-

nexion with the accompanying drawings, it is thought the construction, operation and advantages of the invention will be clear to those skilled in the art.

5. What I claim is:

1. In a split-skirt piston having piston pin bearings located within the confines of the skirt, means carried by the head of the piston and engaging the skirt portion of the piston at a place intermediate the top and bottom ends of the skirt for spreading the skirt, said means comprising a boss having a threaded bore extending at a downward and outward inclination to the head and axis of the piston and an adjusting screw accessible through the head of the piston and having a tapered end to project into the split at an acute angle to the piston wall at a point in transverse alignment with the piston pin bearings.
2. In a split-skirt piston, means carried by the head of the piston and engaging the skirt portion of the piston at a place intermediate the top and bottom ends of the skirt for spreading the skirt, said means comprising a boss integral with the head and land of the piston and having a downwardly and outwardly inclined threaded hole through the same and an adjusting screw in said hole, said screw having a tapered end to cooperate with the split portion of the piston as a spreading wedge and means continuously tending to maintain said tapered end in active contact with the split portion of the piston at all times.
3. In a split-skirt piston, means carried by the head of the piston and engaging the skirt portion of the piston at a place intermediate the top and bottom ends of the skirt for spreading the skirt, said means comprising a boss integral with the head and land of the piston and having a downwardly and outwardly inclined threaded hole through the same and an adjusting screw in said hole, said screw having a split resilient tapered end to cooperate with the split portion of the piston as a spreading wedge and to permit the normal expansion and contraction of the skirt due to temperature changes without disturbing the setting of the screw and its adjustment effect on the skirt.
4. In a split-skirt piston, means carried by the head of the piston and engaging the skirt portion of the piston at a place intermediate the top and bottom ends of the skirt for spreading the skirt, said means comprising a boss integral with the head and land of the piston and having a downwardly and outwardly inclined threaded hole through the same and an adjusting screw in said hole, said screw having a resilient tapered end to cooperate with the split portion of the piston as a spreading wedge and to permit the normal expansion and contraction of the skirt due to temperature changes without disturbing the setting of the screw and its adjustment effect on the skirt.
5. In a split-skirt piston having piston pin bearings, means carried by the head of the piston and engaging the skirt portion of the piston only at a place adjacent a transverse plane normal to the axis of the piston and passing through the piston pin bearings for spreading the skirt, said means comprising a boss having a threaded bore extending at an inclination to the axis of the piston and an adjusting screw accessible through the head of the piston for cooperation with the split portion of the skirt and having a tapered end to project into the split at an acute angle to

the piston wall at a point in transverse alignment to the piston pin bearings, and means detachably securing said boss to the head and against the land of the piston.

6. In a split-skirt piston, means carried by the head of the piston and engaging the skirt portion of the piston for spreading the skirt, said means comprising a boss having a threaded bore extending at an inclination to the axis of the piston and an adjusting screw accessible through the head of the piston and having a tapered split end for cooperation with the split portion of the skirt, the skirt portion of the piston having adjacent the split a pair of spaced lugs constituting a boss having a recess to receive the tapered end of said screw.

7. In a split-skirt piston having piston pin bearings located intermediate the ends of the skirt, means carried by the head of the piston and engaging the skirt portion of the piston only at a place in transverse alignment with the piston pin bearings for spreading the skirt, said means comprising a boss having a threaded bore extending at an inclination to the axis of the piston and an adjusting screw accessible through the head of the piston for cooperation with the split portion of the skirt, the skirt portion of the piston having adjacent the split a pair of spaced lugs constituting a boss having a recess to receive the end of said screw, said recess being shaped to fit the end of said screw and the end of said screw being tapered and springy.

8. In a split-skirt piston, means carried by the head of the piston and engaging the skirt portion of the piston for spreading the skirt, said means comprising a boss extending down into the skirt of the piston having a threaded bore extending at a downwardly and outwardly inclination to the head and axis of the piston and an adjusting screw accessible through the head of the piston for cooperation with the split portion of the skirt, the head of the piston having a threaded counterbore, and a screw plug closing said counterbore and acting as a lock for said screw, the axis of said screw plug being located at an angle to that of said adjusting screw and said screw plug being positioned to bear against the upper end of said adjusting screw.

9. In a piston, a head portion having a continuous peripheral wall provided with ring grooves, a vertically split skirt located below and spaced from the head portion, oppositely disposed connecting elements joining the head portion and the skirt and having piston pin bearings located within the skirt walls in a location intermediate the top and bottom edges of the skirt, a boss carried by the head portion, said boss having a downwardly and outwardly inclined threaded bore, a screw held in said bore and accessible through the top of the piston, said screw having a pointed end to engage in the split of the skirt at the level of the piston pin bearings, said screw having provisions to allow expansion and contraction of the various parts due to usual heat changes without disturbing the normal setting and mechanical-expander-function of the screw.

10. In a piston a head portion having a continuous peripheral wall provided with ring grooves, a vertically split skirt located below and spaced from the head portion, oppositely disposed connecting elements joining the head portion and the skirt and having piston pin bearings located within the skirt walls in a location intermediate the top and bottom edges of the skirt, a boss carried by the head portion and projecting down be-

low the top edge of the skirt, said boss having a downwardly and outwardly inclined threaded bore, a screw held in said bore and accessible through the top of the piston, said screw having a pointed end to engage in the split of the skirt at the level of the piston pin bearings, said screw

having provisions to allow expansion and contraction of the various parts due to usual heat changes without disturbing the normal setting and mechanical-expander-function of the screw.

FREDERICK C. DALTON.
